Primary Examiner — Ian Simmons*Assistant Examiner* — Yuan Yuan(74) *Attorney, Agent, or Firm* — Morrison & Foerster LLP(57) **CLAIM**

The ornamental design for a magnetic pyramid toy as shown and described.

DESCRIPTION

FIG. 1 is a back perspective view of a magnetic pyramid toy showing my new design;

FIG. 2 is a bottom perspective view thereof;

FIG. 3 is a top view thereof;

FIG. 4 is a bottom view thereof;

FIG. 5 is a front view thereof;

FIG. 6 is a back view thereof;

FIG. 7 is a left view thereof; and,

FIG. 8 is a right view thereof.

1 Claim, 8 Drawing Sheets(56)
